COMBINED BOBBY PIN AND PERFUME PELLET HOLDER

Joan Weiss, 325 E. 77th St., New York, N.Y.

Filed Apr. 17, 1964, Ser. No. 79,544

Term of patent 14 years

(Cl. D86—10)

I claim:

The ornamental design for a combined bobby pin and perfume pellet holder, substantially as shown.
